UNITED STATES PATENT OFFICE.

CHESTER L. SHARP, OF LANCASTER, OHIO; GEORGIA SHARP ADMINISTRATRIX OF
SAID CHESTER L. SHARP, DECEASED.

FURNACE.

Application filed October 20, 1920. Serial No. 418,141.

To all whom it may concern:

Be it known that I, CHESTER L. SHARP, a citizen of the United States, and a resident of Lancaster, in the county of Fairfield and State of Ohio, have invented certain new and useful Improvements in Furnaces; and I do hereby declare the following to be a full, clear, and exact description of the invention, such as will enable others skilled in the art to which it appertains to make and use the same.

This invention relates to improvements in furnaces and more particularly to those of the muffler leer type such as are adapted for use in annealing glass articles,—one object of the invention being to so construct the furnace as to provide side combustion chambers adapted for the use of raw or clean producer gas, oil, natural gas or other fuels, and separated from the leer chamber; to obviate the use of preheated air, or natural gas or oil as fuel; to construct the furnace in such manner that uniform temperature throughout the leer chamber, above and below the leer pans or ware conveyor, shall be maintained; to provide means whereby the temperature within the muffler or leer chamber may be increased or decreased as desired; so that the muffler or leer chamber may be increased or decreased as desired; so that the temperature may be increased or decreased at the front or rear of the muffler chamber, as desired, and to provide means for preheating the leer pans or ware conveyor before the glass articles are deposited.

A further object is to provide for the annealing of glass articles in a muffler leer fed from side combustion chambers and to so construct the muffles as to prevent breakage of the muffler tile which allows the gas and products of combustion, from escaping into the muffler chamber.

With these and other objects in view, the invention consists in certain novel features of construction and combinations of parts as hereinafter set forth and pointed out in the claims.

In the accompanying drawings, Figure 1 is a longitudinal sectional view showing an embodiment of my invention; Figure 2 is a vertical transverse sectional view of the muffler leer; Figures 3 and 4 are enlarged fragmentary sectional views taken at right angles to each other, of the muffler leer showing details of construction of the same; Fig-

ure 5 is a sectional view on the line 5—5 of Figure 2; Figure 6 is a section on the line 6—6 of Figure 2, and Figure 7 is a sectional view on the line 7—7 of Figure 5.

1 represents a leer of the muffler type having walls 2 and 3; side walls 4, 4; an arch top 5 having skew abutments at its ends, as at 6, against the side walls, and a bottom 7 made in sections of tile and supported by girders, as at 8, supported at their ends in 60 the side walls 4, and the latter are suitably braced against strains by pairs of upright girders 9 having their upper ends connected by cross rods, as indicated at 10, extending over the arch top 5.

The leer structure above described contains a leer chamber 11 to be heated, and the side walls 12 of this chamber each comprises a plurality of solid tiles having tongue-and-groove joints and each tile having a recessed inner face. The bottom 14 of the leer chamber comprises a plurality of lap-joint tiles having recessed upper faces and the arch top 15 of the leer chamber comprises a plurality of tiles having tongue 75 and groove joints and lower recessed faces. Skew backs 16 are provided at the upper ends of the side walls 12 for the arch top 15. Above the top or roof 15 of the leer chamber, an arch 17 is located and 80 has skew abutments on the side walls 4 of the main leer structure and between the arches 15 and 17 muffle pasages are located as hereinafter explained. The arch 17 is spaced from the crown or arch 5 so that the 85 difference in the expansion between the fire clay of the latter and the fire brick or tile of the arch 17 will be taken up in this space and will prevent leakage of the muffle shapes.

A tunnel 18 communicates with the leer 95 chamber 11 and through this tunnel and through said leer chamber, an endless conveyor 19 passes to carry the glass articles to be annealed. This conveyor passes over drums or wheels indicated at 20 and 21, said 100 wheels or drums being so disposed and of such size that the lower muffle flues will be located between the stretches of the conveyor and serve to heat the same before the articles to be treated are deposited thereon.

Located adjacent to each side of the leer 1 are combustion chambers 22, 22, to which producer gas may be supplied by burners 22^a which receive the gas from a conduit 22^b. The combustion chambers communi- 105 110

cate through passages 23 with muffle passages 24 located between the bottom 14 of the leer chamber 11 and the floor 7 of the leer structure and at respective sides of the 5 center of said bottom, — the muffle passages 23 at one side of the center of bottom 14 being staggered with relation to those at the other side, and alternating with the muffle passages 24, are muffle passages 25 10 which, at one side of the center of the bottom 14 are staggered with relation to the passages 25 at the other side. The bottom muffle passages 24 at each side of the leer structure communicate with vertical muffle 15 passages 26 between the side walls of the leer chamber and the side walls of the leer structure and said vertical passages 26 communicate with muffle passages 27 between the arch top 15 of the leer chamber and 20 the arch 17. Alternating with the vertical passages 26 at each side of the structure are vertical muffle passages 28 which communicate at their lower ends with the bottom muffle passages 25 and at their upper ends 25 with alternate top muffle passages 27. Valves 29 may be provided for the uptake passages 26 for a purpose hereinafter explained.

All of the bottom muffle passages 25 at 30 respective sides of the center of the bottom of the leer chamber communicate with flues 30 and the latter communicates with stack 31, the structure 32 containing the extensions of the flues 30 leading to the stack projecting beyond the leer structure and 35 being disposed between the stretches of the conveyor as shown in Figure 1.

It will be seen that the floor 7 constituting the bottoms of the muffle passages 24, 25 and flues 30 extends the full width of 40 the leer and may extend beyond the stack if desired. This is important to prevent a sudden drop of temperature at the back of the muffle chamber, as has occurred in the operation of muffle leers as heretofore 45 constructed. The sudden drop of temperature above referred to has occurred because there is a draft created under the return pan, and because of the great amount of heat in the muffle chamber, this draft cools the 50 upper pan. This is very detrimental to glass articles for the reason that it throws a strain in the glass and it is impossible to properly anneal articles containing a strain after it has passed out of the muffle chamber. 55 By extending the floor 7 and flues 30 to or beyond the stack, the defects above mentioned will be obviated.

The top of the tunnel 18 hereinbefore referred to, may consist of a plurality of 60 arches 18^a and those arches from the stack to the discharging end of the leer may be provided with openings 18^b. Every other arch is provided with a small stack 18^c in which slide valves 18^d may be located. The 65 openings of the other arches may be covered

with a flat clay closure 18^e. With such construction the operator may gradually cool down the apparatus so that the glass articles will be cool enough to handle when taken off the receiving end. Furthermore, by 70 opening and closing said openings, the operator will be able to obtain any desired fall or drop in temperature that he may desire within the leer.

It will be observed that the products of 75 combustion from the two side combustion chambers will enter the leer structure by way of the passages 23 and flow through the passages 24, thence by the passages 26 to the passages 27; thence from the latter 80 through the passage 28 to the bottom muffle passages 25 and thence through the flues 30 to the stack 31. Thus the heated products of combustion flow in numerous streams around the leer chamber 11, in reverse directions through alternating muffle 85 passages, and operate effectually and uniformly to heat the leer chamber and anneal the glass articles carried through the same by the conveyor.

As two separate exit flues 30 are provided and as the admission passages for products of combustion are equally divided and spaced on both sides of the leer chamber, I am enabled by manipulation of the valves 29, to 90 regulate the temperature of said chamber. Thus, should the temperature on one side of the leer chamber fall, greater draft on the products of combustion may be induced by operating the valves 29 and thus the 100 proper and uniform temperature may be restored. Again, if the operator desires to throw the heat into the front or back part of the muffle chamber, he may do so by operating the valves 29, or if one side is running 105 hotter than the other this can be overcome by operating the valves 29^a in the stack flue.

By my improvements, I am enabled to 110 overcome the defects and objections to prior constructions employing hollow tile involving the cracking and leaking of such tile and the consequent escape of gas to the leer chamber where a deposit on the articles being annealed would result. With my construction as hereinbefore described, the use 115 of hollow tile is avoided and the construction is such that adequate provision is made to allow for expansion and contraction. Again, location of the combustion chambers at the sides of the leer structure, ready access to the burners is afforded.

It may be here stated that it is not absolutely necessary to use cold air in connection with the combustion of the producer gas. If desired, pre-heated air can be used 125 and obtain good results.

Various changes might be made in the details of construction of my invention without departing from the spirit thereof or limiting its scope and hence I do not wish to 130

restrict myself to the precise details herein set forth.

Having fully described my invention what I claim as new and desire to secure by Letters Patent, is:—

1. The combination with a muffle leer having a leer chamber and muffle passages around the same, of combustion chambers communicating with respective sides of said 10 muffle leer, one of said combustion chambers communicating with certain of said passages and the other combustion chamber communicating with others of said passages, and burners discharging into said combustion 15 chambers.

2. The combination with a muffle leer having a leer chamber and two series of muffle passages surrounding said chamber, of combustion chambers communicating with respective sides of said muffle leer, one of said combustion chambers communicating with one series of muffle passages and the other combustion chamber communicating with the other series of muffle passages, and burners 25 discharging into said combustion chambers.

3. The combination of a muffle leer having a leer chamber and two series of muffle passages surrounding said chambers, the 30 muffle passages of one series alternating with the muffle passages of the other series, combustion chambers communicating with respective sides of said muffle leer, one of said combustion chambers communicating with one of said series of muffle passages and the other combustion chamber communicating with the muffle passages of the other series, and burners discharging into said combustion 35 chambers.

4. The combination of a muffle leer having a leer chamber and two series of muffle passages surrounding the same, valves in said passages, combustion chambers communicating with respective sides of said 40 muffle leer and communicating respectively with the respective series of muffle passages, and burners discharging into said combustion chambers.

5. The combination of a muffle leer having a leer chamber, an endless conveyor having its upper stretch passing through said chamber, said muffle leer having muffle passage surrounding said chamber, certain of said muffle passages disposed between the 50 stretches of said endless conveyor, combustion chambers for feeding products of combustion to said passages, and burners discharging into said combustion chambers.

6. The combination of a muffle leer having a leer chamber and two series of muffle 60 passages surrounding said leer chamber, the passages of one series alternating with the passages of the other series, a separate combustion chamber communicating with the

inlet ends of each series of passages, flues 65 under the leer chamber communicating with the outlet ends of the muffle passages of the two series, and burners discharging into said combustion chambers.

7. The combination of a muffle leer having a leer chamber and muffle passages surrounding the same, combustion chamber for feeding products of combustion to the inlet ends of said passages, burners discharging into said combustion chambers, an endless 75 conveyor having its upper stretch passing through the leer chamber, outlet flues communicating with the outlet portions of said passages and extending beyond the muffle leer, the outlet portions of said passages 80 and said flues disposed between the stretches of said endless conveyor.

8. A muffle leer comprising side and end walls and an arch top, a leer chamber having its walls, bottom and arch composed of jointed tile sections, an arch of solid members spaced from the arch of the leer chamber and also spaced from the arch of the muffle leer and resting on the side walls of the latter, muffle passages surrounding said leer 90 chamber, means for supplying products of combustion to the inlet ends of said passages, and flues communicating with the outlet ends of said passages.

9. A muffle leer comprising upright walls, 95 an arch top and a bottom member, a leer chamber having side walls, a bottom member and an arch top all composed of jointed tile, the arch top having a skew mounting on the side walls, an arch spaced above the 100 arch of the leer chamber and spaced below the arch of the muffle leer and having skew mountings on the side walls of the muffle leer, muffle passages surrounding said leer chamber and having inlet portions for products 105 of combustion, and flues communicating with the outlet portions of said passages.

10. A muffle leer having upright walls, a top and a bottom, a leer chamber located within the muffle leer and spaced from the 110 top and bottom and side walls thereof, two series of muffle passages surrounding said leer chamber, the passages of one series alternating with those of the other series, said passages having inlet portions for products 115 of combustion, flues communicating with the outlet portions of said passages, means for regulating the passage of products of combustion through said passages combustion chambers, and burners discharging into said 120 combustion chambers.

In testimony whereof, I have signed this specification in the presence of two subscribing witnesses.

CHESTER L. SHARP.
